UNITED STATES PATENT OFFICE

102,117

DESIGN FOR A PRINTED TEXTILE FABRIC OR SIMILAR ARTICLE

Marion R. Hamre, Brooklyn, N. Y.

Application October 24, 1936, Serial No. 65,466

Term of patent 3½ years

To all whom it may concern:

Be it known that I, Marion R. Hamre, a citizen of the United States residing in the Borough of Brooklyn, city of New York, county of Kings, and State of New York, have invented a new, original, and ornamental Design for a Printed Textile Fabric or Similar Article, of which the following is a specification, reference being had to the accompanying drawing, forming part thereof.

The figure is a plan view of a printed textile fabric showing my new design.

The area within the dot and dash lines shows one complete unit of the design. The repeats are arranged in vertical rows and adjacent vertical rows are one-half a complete unit offset so that the angle of the complete unit indicated by letter A corresponds with the angle B of one of the repeats in an adjacent vertical row.

I claim:

The ornamental design for a printed textile fabric or similar article as shown and described.

MARION R. HAMRE.
